ENGINE FUEL GAS METERING DEVICE

Sam P. Jones, Dallas, Tex., assignor to J & S
Carburetor Co., Dallas, Tex., a corporation of
Texas

Application December 18, 1952, Serial No. 326,700

3 Claims. (Cl. 48—180)

1

This invention relates to new and useful improvements in engine fuel gas metering devices. In internal combustion engines having only a few cylinders, such as one and two cylinder engines, some difficulty has been experienced in metering the fuel gas supply properly to the intake manifold. This is especially true of four-cycle engines where the manifold pressure is employed as the load indicating means and is utilized to regulate the fuel gas supply. Since engine speed does not necessarily indicate engine load, the pressure in the intake manifold of the engine is the most widely employed factor for controlling fuel gas supply. In a one or two cylinder, four-cycle engine, however, a depressed manifold pressure exists only during the suction stroke of the engine, and throughout substantially the entirety of the other three cycles the pressure in the intake stack of the engine as well as the intake manifold thereof, is substantially atmospheric. Hence, the manifold pressure is indicative of the loading of the engine only during the suction stroke, and to afford efficient engine operation, the engine loading must be sensed during the suction stroke and the fuel metered accordingly. Metering devices are mechanical structures and cannot operate instantaneously. For this reason, it has been found extremely difficult, if not virtually impossible, to provide a device which would respond to manifold pressure to meter the fuel gas and would respond sufficiently quickly to accomplish this desired result during the very short period the manifold pressure is depressed. As a necessary compromise such fuel metering devices have necessarily been set rather rich in order to insure adequate fuel supply to the engine, and there has necessarily been a wastage of fuel with the net result that the engine does not display as much economy in fuel consumption as would be desired.

It is therefore, an important object of this invention to provide an improved metering device for the fuel gas of engines which is responsive to manifold pressure to meter fuel to the engine, and which, upon actuation during the suction stroke of the engine both senses and retains the degree of depression of the manifold pressure whereby the fuel gas metering structure is held substantially at the desired setting throughout all four strokes of the engine during a single cycle, and thus renders of no effect the inability of mechanical devices to respond instantaneously to a pressure change.

Another important object of the invention is to provide a device of the character described hav-

2

ing also means for slowly bleeding off the pressure depression received and retained during the suction stroke of the engine whereby the metering structure is constantly readjusted in accordance with the loading of the engine and brought into the proper condition for metering fuel in proper yet economical quantities to the engine as the demand of the engine for such fuel may vary.

A particular object of the invention is to provide an improved metering valve for metering fuel gas to internal combustion engines, the valve having pressure responsive means for actuating the same and reducing the availability of fuel as the manifold pressure depression increases, there being a conductor between the pressure-responsive means and the intake manifold of the engines with a check valve therein whereby pressure depression may be communicated to the pressure-responsive means from the intake manifold, but the dissipation of the reduced pressure condition acting upon the pressure-responsive means being prevented by the check valve; and further, having restricted pressure bleed means for by-passing the check valve and permitting an increase of the pressure acting on the pressure-responsive means.

An additional object of the invention is to provide a device of the character described which is particularly adapted for use with two cylinder engines having two intake stacks and which may readily be incorporated into the conventional two-barrel carburetor or gas mixer.

Yet another object of the invention is to provide a device of the character described which will effect an appreciable economizing of fuel over the intermediate load ranges of one and two cylinder, internal combustion engines.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a longitudinal, sectional view showing a device constructed in accordance with this invention connected to the intake stack of an internal combustion engine.

Fig. 2 is a transverse, sectional view showing a modification of the invention connected to the intake stacks of a double-barrel carburetor.

Fig. 3 is a graph illustrating the fuel economy of this invention as compared to the economy of a conventional fuel gas metering device, the two curves being plottings of specific fuel consump-

tion in pounds of fuel per brake horsepower per hour plotted against actual brake horsepower being delivered by the engine.

Fig. 4 is a longitudinal, sectional view illustrating a modification of the invention applied to a two barrel carburetor.

Fig. 5 is a transverse, vertical, sectional view taken upon the line 5—5 of Fig. 4, the view being enlarged.

Fig. 6 is a longitudinal, sectional view taken upon the line 6—6 of Fig. 5.

Fig. 7 is an enlarged, fragmentary, transverse sectional view of one of the check valve structures, and,

Fig. 8 is a horizontal, sectional view taken upon the line 8—8 of Fig. 7.

In the drawings, the numeral 10 designates the air intake stack of a carburetor or fuel mixer for internal combustion engines. The carburetor may be of the single intake stack or single barrel type, as shown in Fig. 1, or may be of the two or double barrel type, as shown in Fig. 2. The intake stack is provided with the usual Venturi section 11 having projecting thereinto a fuel feed pipe 12, and the usual throttle valve 13 is situated downstream of the Venturi section. This structure is connected to the intake manifold (shown in dotted lines at 14 in Fig. 1) of the internal combustion engine to which the fuel mixture is to be supplied. It is quite conventional to use a single barrel carburetor, as shown in Fig. 1 upon single cylinder engines and to employ a double barrel carburetor, as shown in Fig. 2, on two cylinder engines.

A metering valve structure is connected to the intake stack and includes a suitable tube 15 having an inlet nipple 16 adapted to receive a flexible hose or other conductor through which the fuel is supplied. The fuel inlet nozzle 12 is connected by a fuel conductor or pipe 17 to the bore of the tube 15, communicating therewith through one side wall. A suitable sleeve valve 18 is slideably mounted within the bore of the tube 15 and is provided with a lateral port 19 adapted to register with the tube 17 to permit the flow of fuel to the nozzle 12. Obviously, axial movement of the member 18 within the tube 15 will uncover a greater or lesser area of the bore 17, and hence, the axial position of the member 18 as it reciprocates within the tube 15 will control the quantity of fuel supplied through the air intake stack 10.

For controlling movement of the valve member 18, the tube 15 is flared at one end to form a dished portion 20 having a marginal outwardly extending flange 21. A dished cover plate 22 having a central, cylindrical dome 23 and an outwardly extending marginal flange 24, is connected by the flange 24 to the flange 21, and a flexible diaphragm or pressure responsive member 25 is clamped between the flanges. Suitable bolts 26 may be used for joining the flanges together.

The valve member 18 is of sleeve-like construction and has an open end 27 facing the inlet nipple 16, and a closed end 28 abutting the diaphragm 25. The diaphragm is clamped to the closed end of the valve sleeve by means of a plate 29 and screws 30. A coiled spring 31 is positioned within the dome 23 and confined between the closed upper end of said dome and the plate 29 so as to constantly urge the diaphragm toward the inlet end of the tube 15. This action simultaneously moves the valve sleeve 18 into the position shown in Fig. 1 in which the port 19 is in full registry with the bore of the tube 17 and the metering valve structure is open to its fullest extent. A

stop bolt 32 is threaded into the top of the dome 23 and extends therethrough toward the plate 29 so as to limit movement of the plate and the diaphragm, along with the valve sleeve 18, toward a closed position. A lock nut 33 is provided for holding the bolt 32 in its adjusted position.

The air intake stack is provided upon one side wall with a boss 34 through which a passage or pressure conductor 35 extends to the interior of the cover plate 22. The passage 35 is enlarged at 36 adjacent the bore of the stack 10, and a check valve ball 37 is positioned within the enlarged portion so as to function as a check valve and prevent the flow of fluid under pressure from the intake stack through the passage 35. There is also provided a passage 38 bypassing this check valve structure and having therein a restricted portion 39 of very small diameter. The function of this restricted bypass conductor arrangement will be described more fully hereinafter.

In the operation of this form of the device, and assuming the engine not to be in operation, atmospheric pressure will exist throughout the intake stack and the counterbore 36, and through the bleed passage 39, will be established in the bore 35. Hence, the spring 31 will be effective to move the diaphragm away from the cover plate 22 and will align the port 19 fully with the bore of the tube 17. As the engine is started, and assuming the throttle valve 13 to be nearly closed, a relatively high vacuum will be established downstream of the throttle valve, and this vacuum will be communicated through the counterbore 36 since the same opens into the intake stack downstream of the throttle valve. This vacuum will lift the valve ball 37 and be communicated through the passage 35 to the diaphragm 25 and pull the plate 29 against the stop bolt 32. At this point, the port 19 will be misaligned with the tube 17 to its greatest extent and the flow of fuel to the intake stack will be at a minimum. In this idling condition of the engine the proper fuel mixture may be obtained by adjustment of the bolt 32 so as to open the metering sleeve valve 18 formed by the tube 15 and the sleeve element 18 to the minimum desired extent.

It is to be noted that this vacuum or low pressure created within the intake manifold by operation of the engine exists in reality only during one stroke of each cycle or approximately 25% of the time. If no means were provided for preventing such action, the spring 31 would force the metering valve to its wide open position during the remaining three quarters of each cycle with the net result that an excessive flow of fuel would be encountered at least during the initial portion of the intake stroke, and excessive usage of fuel would result.

The check valve 37 and bleed passage 39 prevent this occurrence, however, the check valve functioning to hold the metering valve in a partially closed position and preventing air or gas from entering the passage 35 so as to relieve the partial vacuum established within the space defined by the diaphragm and the cover plate 22. At the same time, the restricted by-pass passage 39 prevents the indefinite retention of this condition, and fluid will gradually bleed through it around the check valve so as to bring the pressure conditions within the aforesaid space into agreement with the manifold pressure existing during the suction stroke.

As the throttle valve is opened, and the load upon the engine is increased, it is desirable that more fuel be fed to the intake stack, and this

also occurs by reason of the check valve and restricted bleed passage structure. As the engine load increases, the vacuum in the intake manifold decreases, and unless this vacuum is greater than that existing within the passage 35, the check valve will not be lifted from its seat. Instead, a gradual flow of fluid through the restricted passage 39 takes place and the pressure exerted upon the diaphragm is brought into agreement with the manifold pressure. A reduction of the suction acting on the diaphragm in opposition to the spring 31 permits the diaphragm to move the metering valve toward a more open position and to increase the fuel flow as required. This action continues as the throttle valve is moved to a full open position, at which point, the spring 31 is effective to move the metering valve to its full open position and to supply the maximum quantity of fuel. Any time the load on the engine is reduced and the throttle valve is closed, there will be exerted during the suction stroke of the engine a vacuum or reduced pressure which will lift the valve ball 37 from its seat, communicate this partial vacuum to the diaphragm 25, and shift the metering valve into the position determined by the degree of vacuum exerted. Whenever the throttle valve is opened wider, the check valve ball 37 remains seated and pressure equalization takes place at a controlled rate through the restricted passage 39 to permit further opening of the metering valve.

The device thus functions somewhat as a time delay mechanism and slows the responsiveness of the metering valve to an extent sufficient to hold the valve in an adjusted position throughout a full cycle of operation of the engine. As the engine load is increased or decreased and the manifold pressure varies accordingly, this pressure is communicated in a controlled manner to the diaphragm 25 to vary the setting of the metering valve accordingly, and at the same time, the metering valve is protected against the rapidly fluctuating pressures existing downstream of the throttling valve occasioned by the connection of only one or two cylinders of an engine to the intake stack.

This type of carburetor depends upon the flow of air through the intake stack to create a reduced pressure area or zone within the venturi 11, and by means of this reduced pressure, to draw fuel through the nozzle 12 from the source of fuel supply. The degree of suction exerted through the nozzle 12 does not vary in strict accordance, however, with the flow of air through the venturi. At low engine loads, the air velocity through the venturi is low and the suction exerted through the fuel nozzle 12 may be inadequate to supply sufficient fuel. At intermediate loads, the structure may be nicely in balance, but at high loads where the air velocity through the venturi is high, too much suction may be exerted through the nozzle and hence, too rich a fuel mixture may be supplied. It has been common practice heretofore to provide multiple barrel carburetors to overcome this objectionable feature, and hence, even in a two cylinder engine, a double-barrel carburetor may be employed. Since each barrel intake stack supplies one of the engine cylinders, the problem in such an installation in properly sensing the manifold pressure and applying the same to regulate the fuel supply may be quite as severe as that encountered in a single cylinder engine having a single barrel carburetor. The present invention lends itself readily to utilization of a double-barrel carburetor as shown in

Fig. 2. In this form of the invention, fuel is admitted through the inlet end 40 of an elongate metering valve tube 41, and pipes or conductors 42 extend through the side wall of the tube 41 to the fuel intake nozzles 43 of the two air intake stacks 44. A valve sleeve 45, similar to the sleeve 18 is slidably mounted within the tube 40 and is provided with a pair of lateral ports 46 adapted to register with the bores of the tubes 42. A diaphragm and spring structure substantially the same as that shown in Fig. 1 is enclosed with a housing 47 connected to one end of the tube 41, and this housing is in turn connected to the air intake stacks in order to respond to the manifold pressure exerted downstream of the throttle valve. As will appear more fully herein-after, this metering valve structure also responds to engine load conditions and differs from the form of the invention shown in Fig. 1 primarily by metering fuel to two intake stacks rather than a single intake stack. The operation is substantially identical.

Since the air intake stacks of double barrel carburetors are often formed in a single integral unit, this invention may desirably be applied thereto as shown in Figs. 4 to 8. As illustrated in these figures, there is provided a carburetor body 48 having therein a pair of parallel barrels or intake stacks 49. Each of the intake stacks is formed with a Venturi section 50 into which a gas inlet nozzle 51 extends. The conventional choke 52 is provided upstream of the venturi and the throttle valve or throttle plate 53 is mounted downstream of the Venturi section.

The tube 41 of Fig. 2 is clamped directly to the side of the body 48 and secured thereto by a block 54 and bolts 55. The diaphragm housing 47 is carried upon one end of the tube 41, and the opposite end thereof, is, of course, adapted to be connected to the source of fuel supply by the nipple 40. The tube 41 extends transversely of the axes of the intake stacks in the manner illustrated in Fig. 2, and a hose or other suitable conducting member 56 extends from the diaphragm housing 47 for connection to the intake stacks.

Since these carburetor bodies are conventionally formed with flanges at each end for ready attachment to an air cleaner or other device (not shown) at the intake end, and to the intake manifold of the engine at the downstream or outlet end, the connection of the hose 56 into the intake stacks may desirably be made through the downstream flange. As shown in Figs. 4 and 6, the body 48 is provided with an outwardly extending flange 57 at its outlet or downstream integrally with said flange and with the carburetor body at a point intermediate the two intake stacks. A recess 59 is drilled or otherwise formed in the boss 58 and extends upwardly at an angle therein. The recess carries internal screw threads 60 which receive a screw-threaded nipple 61 to which the hose 56 is connected.

On each side of the recess 59 are formed screw-threaded bores 62, extending vertically upwardly through the lower edge of the flange 57 and communicating at their upper ends through reduced passages 63 with the interiors of the intake stacks 49 downstream of the throttle valves 53. Angular passages 64 provide communication between the recess 59 and the bores 62.

A screw-threaded check valve plug 65 is received in each of the bores 62. Each of the plugs 65 has an axial screw-threaded bore 66 in its upper end closed by plugs 67 having a plurality

of eccentrically-positioned, longitudinally-extending, flow passages 68. The lower ends of the bores 66 are free of screw threads to form cylindrical chambers 69 receiving check valve balls 70, and the lower extremity of each of the chambers 69 communicates through an axial passage 71 with a bore 72 extending transversely of each of the plugs 65. A valve seat 73 formed in the bottom of each of the chambers 69 receives the valve balls 70 whereby the latter may close off flow through the passages 71 and 72.

The outer periphery of the plugs 65 are cut away to form annular grooves 74 around the plugs and the passages 72 open into said grooves. As shown in Figs. 5 and 7, when the plugs 65 are positioned within the bores 62, the grooves 74 register with the passages 64, and thus, communication is established from the recess 59 through the branch conductors formed by passages 64 and the grooves 74, as well as the passages 72 and 71 of each of the plugs 65, and the remaining passages leading to the stacks 49. There is further provided in each of the plugs a very small, restricted passage 75 extending radially from the chambers 69 to the grooves 73. Since the inner ends of the restricted passages 75 are above the valve seats 73, said restricted passages remain in communication with the intake stacks at all times through the passages 63 and 68.

The operation of this modification of the invention is the same as that previously given, the ball 70 and seat 73 performing in the same manner as the check valve ball 37, while the restricted passages 75 perform the function of the restricted passage 39 of the form of the invention shown in Fig. 1. The particular structure illustrated is beneficial in that the check valve plug structures 65 are readily accessible and may be easily removed and replaced as desired. Thus, plugs having different diameters of restricted passages 75 may be substituted in any particular carburetor structure, the check valve structure may be removed for cleaning, repair, or replacement, or for cleaning out of the passages 63 and 64.

The improved performance of the present invention as compared to conventional devices is graphically illustrated in Fig. 3 of the drawings by fuel consumption curves obtained on dynamometer tests of a commercial two-cylinder engine operated with its conventional carburetor, and of the same engine operated with a carburetor constructed in accordance with this invention. The engine under test was a 35 H. P. engine and the fuel consumption of the engine, using L. P. G. fuel was determined in pounds per brake horsepower per hour for each of the two carburetors over the entire operating range of the engine. The upper, solid-line curve A is a plot of the results obtained during testing of the engine with its conventional carburetor. The lower, dotted-line curve B is a plot of the fuel consumption observed when the engine was operated with a carburetor constructed in accordance with this invention. These two curves show clearly that although the two carburetors resulted in approximately the same fuel consumption at full load and under idling conditions, appreciable fuel savings were obtained in the intermediate load ranges where such engines operate a large percentage of the time. Using as an example, an engine load of 25 brake horsepower which may be considered an average loading for engines of this type, a reduction in fuel

consumption of approximately 0.08 of a pound of fuel per brake horsepower per hour is shown. In a ten-hour operating day, this means a fuel saving of approximately four gallons of L. P. G. fuel. Comparable fuel economy was observed in the range from 15 to 30 brake horsepower loading of this 35 H. P. engine. The fuel economy resulted from the ability of the carburetor constructed in accordance with the invention to respond accurately to the engine manifold pressure during the suction stroke of the engine whereby fuel could be metered to the engine in accordance with the requirements therefor, and whereby both excessive and/or insufficient supplies of fuel to the engine were avoided.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A fuel gas metering device for an internal combustion engine having a fuel intake connected to an air intake stack with a throttle valve therein, said device including, a fuel conductor for supplying fuel to the engine fuel intake, a metering sleeve valve connected into the fuel intake conductor, said valve having a movable valve sleeve reciprocable to open and close the valve, a diaphragm connected to the valve sleeve for reciprocating the sleeve, the diaphragm having one side enclosing a chamber within which the application of a sub-atmospheric pressure will bias the metering valve toward a closed position, a spring biasing the valve toward an open position, a pressure conductor connected between the chamber and a point in communication with the air intake stack between the throttle valve and the engine intake, a check valve in the pressure conductor arranged to open only when the pressure in the chamber is greater than the pressure at said point, and a by-pass conductor communicating between the chamber and a point in communication with the air intake stack between the throttle valve and the engine intake, the by-pass conductor being arranged in parallel with the check valve so as to by-pass the same and having a restriction therein.

2. A fuel gas metering device for an internal combustion engine having an intake connected to a pair of air intake stacks with throttle valves therein; said device including, a metering sleeve valve carried by the intake stacks and extending transversely across the exteriors of said stacks, fuel conductors opening into the interior of the sleeve valve and extending into each of the stacks, a valve sleeve slideably mounted in the valve and having ports adapted to be aligned with the fuel conductors, means for supply fuel gas to the ports, pressure-responsive means connected to the valve sleeve for reciprocating the same in the valve, the latter means enclosing a chamber within which the application of a sub-atmospheric pressure will bias the valve toward a closed position, means biasing the valve toward an open position, a pressure conductor leading from the chamber, a pair of branch pressure conductors, each of the branch conductors communicating between the first pressure conductor and a point in communication with one of the air intake stacks between the throttle valve thereof and the engine intake whereby the first conductor is placed in communication with both

air intake stacks through said branch conductors, a check valve in each of the branch conductors opening away from the first pressure conductor, and a restricted orifice in each of the branch conductors arranged in parallel with the check valves and by-passing the latter.

3. A fuel gas metering device as set forth in claim 2, wherein the intake stacks have a marginal flange for connection to the engine intake, the flange having formed therein the branch conductors and having a recess in communication with the branch conductors, the first pressure conductor being connected into said recess, plugs removably positioned in the branch conductors and extending vertically in the flange from the exterior thereof, the check valves being gravity closing and carried by the plugs so as to be removable from the exterior of the flange,

5 the plugs having exterior annular grooves in communication with the recess and the metering valves sides of the check valves, and the restricted orifices being formed in the plugs and extending from said grooves to the intake stack sides of the check valves.
